Carpets

NO. 11,509

Nov 18, 1879

UNITED STATES PATENT OFFICE.

HUGH CHRISTIE, OF MELROSE, NEW YORK, N. Y., ASSIGNOR TO THE BIGELOW CARPET COMPANY, OF CLINTON, MASS.

DESIGN FOR CARPET.

Specification forming part of Design No. **11,509**, dated November 18, 1879; application filed September 19, 1879.
[Term of patent 3½ years.]

To all whom it may concern:

Be it known that I, HUGH CHRISTIE, of Melrose, New York city, county and State of New York, have invented a new and original Design for a Carpet, of which the following is a specification.

The accompanying photographic illustration represents a face view of my newly-designed carpet.

This invention relates to a new and original design for carpets, oil-cloths, and similar fabrics, and for the border of the same.

It consists of the new ornamentation and grouping of the figures, hereinafter more fully described.

In the photographic illustration, the letter A represents the body of the carpet. B is the border of the same. Upon the body A is represented a Chinese pagoda, a, partly hidden by leaves and flowers b.

d and e are floral groups, and f is a smaller floral group containing fern-leaves. Upon the background A are also represented three groups, g, h, and i, of lattice-work. The group g consists of a series of parallel curved bars traversed by diagonal bars. This group is represented as casting a shadow, thus producing a peculiar striking effect. It unites the floral groups e and f. The group h is similar to one end of the group g, and is also repre-

sented as casting a shadow. The group i is composed of a series of diagonally-traversing bars.

Upon the body A are further shown several smaller connecting ornaments in shape of leaves and flowers. The border B contains a substantial reproduction of the pagoda a, flowers b, and group g.

I claim—

1. The design for a carpet, consisting of the figures a, b, d, e, and f, and connecting ornaments, substantially as shown.
2. The design for a carpet, consisting of the group g, substantially as shown.
3. The design for a carpet, consisting of the group h, i and intervening and connecting leaves and flowers, substantially as shown.
4. The design for a carpet, consisting of the groups e, f, and g, substantially as shown.
5. The design for a carpet, consisting of the figures a, b, d, e, f, g, h, and i, substantially as shown.
6. The design for a carpet, consisting of the groups a b g and connecting ornaments, substantially as shown.

HUGH CHRISTIE.

Witnesses:

CHRISTINA CHRISTIE,
TOMPSON B. MOSHER.
